PNEUMATIC COAL CLEANER

Alwyn G. Oppy, Bedford, Pa.

Application March 2, 1933, Serial No. 659,370

14 Claims. (Cl. 209—466)

This invention relates to machines for cleaning slack or fine coal from one inch to a fraction in size by removing such free foreign matter therefrom as is gravimetrically heavier than the coal and constitutes in certain features an improvement upon my former Patent 1,792,440 granted February 10, 1931. The invention relates particularly to a cleaner in which air is used as a flotation medium to support a bed of coal while the bed is moving gradually toward its discharge point, the supporting or flotation medium permitting the descent of the heavier foreign particles to a position below the bed of coal.

The demands of the coal trade require a by-product slack whenever possible and a stoker slack where the inherent properties of the coal do not permit a by-product to result. A reduction in high "ash" or high waste products to a salable ash is also demanded and it is required that these results shall be accomplished with a low moisture content. These many requirements present a problem very difficult of solution and it is the general object, therefore, of this invention to provide a coal cleaning machine which experience and tests have shown will secure this result.

These results are secured by certain novel features which will now be stated.

First.—The coal to be cleaned is passed as a thin ribbon or layer over a perforated deck or series of decks, each deck having a constantly decreasing slant or curvature, each deck being relatively steep at its entrance end and nearly horizontal at its discharge end, the coal and slate while passing over the deck being supported by an air blast.

Second.—The several decks are vibrated vertically and longitudinally, the vibrations decreasing from the entrance end of each deck toward the discharge end thereof and from the first deck of the series to the last or, in other words, the amplitude of the vibration decreases from the origin of the flow to its discharge. More particularly, in this connection, the cleaner has a vibration of about one-eighth of an inch at or near the high end or feed end, the rapidity of these vibrations being such as necessary for the wettest coal to be treated. The discharge end of the cleaner is swingingly mounted so that a motion of diminishing magnitude is secured from the entrance end to the discharge end, which acts in conjunction with the slope of decreasing grade to make a cleaning result grading from a relatively violent action to a gentle and very sensitive treatment, thus securing the effect that all kinds of refuse and pieces of various size must separate and the refuse sink at those points where ideal conditions for such settlement exist.

Third.—The provision of transversely extending retarding bars disposed slightly above the

deck, the bars being arranged serially to conform to the variation in the slant or curvature of the deck, impurities passing downward between these bars and passing down the deck beneath the bars.

Fourth.—The provision of a trap or depression at the lower end of the deck in which the slate or other impurities collect, this collection of these impurities at this point squeezing out the light coal particles under the action of gravity.

Fifth.—The provision of a mechanically operated gate at the discharge end of each deck, acting intermittently to permit only a portion of the refuse to be dumped at each opening of the gate, thus providing for a controlled refuse discharge or removal which is entirely positive in its action and is adjustable to variations of raw feed ash encountered from different mines and dumping into the same tipple.

Other objects will appear in the course of the following description.

My invention is illustrated in the accompanying drawings, wherein:—

Figure 1 is a top plan view of my improved coal cleaner;

Figure 2 is a side view thereof;

Figure 3 is a vertical, longitudinal section;

Figure 4 is an enlarged sectional view of the gate structure and portion of the deck adjacent;

Figure 5 is a section on the line 5—5 of Figure 3;

Figure 6 is a section on the line 6—6 of Figure 3;

Figure 7 is a section on the line 7—7 of Figure 3;

Figures 8, 9, 10, and 11 are diagrammatic edge elevations of different forms of decks.

Referring to these drawings, 10 designates parallel channel iron beams constituting a channel iron frame having the transverse members 11 at its ends, the intermediate transverse members 12 and being supported by the supporting timbers 13. This frame is disposed at an angle to the horizontal. Disposed above this supporting frame is a hopper designated generally 14 having side walls 15 which extend longitudinally the entire length of the machine and are provided at their upper margins with the outwardly turned flanges 16 for a purpose to be later stated. This hopper or shoe is supported along its lower margin upon the two parallel channels 17 which constitute refuse chutes (see Figure 7). These channels as illustrated in Figure 2 extend beyond the forward edge of the shoe 14 and may or may not, as desired, extend to the rear or entrance end of this shoe. As illustrated, they terminate short of this entrance end. Each of these channels or refuse chutes 17 is pivotally supported at its forward end upon a link 18 which is pivotally mounted at 19 upon the corresponding beam 10.

Supported in suitable bearings 20 upon the beams 10 adjacent the rear ends of the channels 11 is a transverse shaft 21 driven by any suitable means and carrying an eccentric 22. Each of these channels carries an eccentric ring 23 which coacts with the eccentric 22 and thus as the eccentrics are rotated, the rear ends of the channels and thus the rear end of the shoe are given an oscillating motion of very small amplitude. Under average circumstances the amplitude of this vibration will be only about one-eighth of an inch, but it is to be understood, of course, that the eccentric may have any degree of eccentricity and thus secure any desired amount of shaking motion in a vertical plane for the shoe.

Disposed below the shoe are one or more rotary fans, the casings of which are designated 24 and 25 and the fans may be of any character, preferably of a Cyclone type. The fan casings 24 and 25 are extended in a spiral upward as at 26. These fans may be of the same size or may be of different sizes and while I have shown two fan casings, it is to be understood that any number may be used.

25 I have illustrated the fan casing 24 as being connected to a trunk 27 by a rectangular connection 28 of iron or any other suitable material, this trunk 27 extending upward between the beams 10 and being connected by a flexible coupling 29 to the forward end of the shoe 14. The fan casing 25 is connected by a coupling 29 to the bottom of the shoe adjacent the discharge end of the shoe.

The shoe, as illustrated, is divided into three compartments by the transverse walls 30, 31, and 35 32.

The trunk 27 from the fan casing 24 discharges into the first compartment of the series designated A and the fan casing 25 discharges into the two compartments designated B and C, it being understood, however, that separate fan casing with its fan might be used for each one of these compartments A, B and C, or one fan for all compartments.

Disposed at the discharge side of each compartment are the refuse discharge chutes 33 which are designated also by the letters a, b and c to correspond to the compartments A, B and C to which they are related. Disposed over the top of each compartment but below the upper edges of the side walls 15 are the several decks 34, 35 and 36. These decks are perforated so as to permit the air from the compartments below the decks to pass upward through the decks and float the coal lying upon the decks.

55 Each of these decks is curved downward and forward or toward its discharge end, the curvature being such that the entrance end of each deck is relatively steeply curved while the discharge end of each deck lies nearly in a horizontal plane, as shown diagrammatically in Figures 8 to 11. This is a very important feature of my invention. Each deck at its discharge end is downwardly inclined at 37 to form a refuse pocket and discharging on to the first deck 34 is the raw feed chute 38 which forms the end wall of the shoe. The mixed coal and slate is discharged on to this chute 38 in any suitable manner and passes downward on to the deck 34 which separates a certain portion of the slate or other impurities from the coal. The impurities so separated gather in the refuse pocket 37 and pass into the corresponding refuse chute a, then the coal passes over on to the deck 35, refuse is again separated from it and discharged into the refuse chute b and the coal

passes on to the deck and the refuse therefrom is discharged into the chute c.

Disposed immediately above the curved portion of the deck are a plurality of transversely extending flow bars 39 which are supported in spaced relation to the deck and which are arranged in a curved line conforming to the curvature of the deck. These bars are gaging bars and are mounted as shown in Figure 5. As shown in this figure, the extremities of the flow bars are provided with clamps 40 each of which engages the horizontal inwardly projecting flange of an angle iron 41 which is disposed against the inside face of the side wall 15 of the shoe. Engaged with the ends of each angle iron 41 is an angular supporting bolt 42 whose lower end extends through a slot 43 formed in the side wall 15. A nut 44 is threaded on the angular end of the bolt 42 and bears against the face of the corresponding angle iron 41 while exteriorly of the wall 15, each bolt carries a washer 45 and a nut 46 clamping against the wall 15. The upwardly extending portion of the bolt 42 passes through an aperture in the flange 16 of the wall 15 and is threaded and provided with the two nuts 47 and 48 which clamp upon this flange. Thus it will be seen that the flow gaging bars 39 may be raised or lowered relative to the corresponding deck so as to space these flow bars just the proper amount from the face 30 of the deck. The coal passes over the upper faces of these flow bars while the slate sinks by gravity downward through the spaces between the flow bars and into the space between the upper face of the deck and the under faces of 35 the flow bars.

At the end of each deck, there is provided a gate designated generally 49 formed of a strip of metal bent upon itself to surround a transversely extending shaft 50. The inner fold of 40 each gate is shorter than the outer fold or leaf and provided with an adjustable sweeper 51.

The outer leaf or fold of the gate extends downward beyond and normally bears against the forward edge of the corresponding deck. 45 The shaft 50 is vertically adjustable, bearing 52 of this shaft being mounted upon a supporting plate 53 engaged by the lower angular end of a bolt 54 constructed in the same manner as the bolt 42 and extending through the flange 16 and 50 adjustably engaged with this flange in a manner which is obvious from Figure 6 so that the shaft of the gate and the gate itself may be raised or lowered. The sweeper 51 is made adjustable to compensate for this bearing adjustment. 55

The gates are designed to be opened intermittently to permit the discharge of refuse from the pocket 37 into the corresponding refuse chute a, b or c and to this end the shaft of each gate at one end is provided with an arm 55, 60 this arm being formed in two sections adjustable upon each other and held in adjusted position by the bolts 56 as shown in Figure 2. To the extremity of this arm is connected an adjustable link 57 which at its lower end is pivotally connected to an operating arm 58 pivoted in any suitable manner at 59 and provided with an adjustable plate 60 upon which a cam 61 wipes, this cam being rotatably mounted upon the side beams 10. There is a cam for each one of these 70 arms 58 and inasmuch as there are three gates, there will be three arms 58 and three cams. Each cam is preferably operated by a separate and independent motor, as for instance, a servomotor, the casings of which are designated re- 75

spectively 62, 62a and 62b. By the term "motor" I do not wish to be limited to a self-driven mechanism, though I may use mechanism of this kind for driving each of the cams, but I have shown for this purpose at 62, 62a and 62b the casing of a selective speed transmission gear which is found upon the market and which forms no part of my invention whereby each cam may be driven at a selected speed and independently of the selected speed of any other cam. As illustrated, the first cam of the series which operates the gate for the compartment A is driven from a speed transmission gearing, (which may also include a driving motor, if desired), the casing of which is designated 62 by means of a belt, sprocket chain or like element 63 extending over a pulley or sprocket wheel 64, the shaft of which carries a small sprocket wheel or pulley 65 from which extends a chain or belt 66 passing over a pulley or sprocket wheel 67 mounted on the shaft of the first cam of the series. This shaft also carries the pulley or sprocket wheel 68 over which a chain 69 passes over a sprocket 70 to a second speed transmission mechanism 62a having in turn a driven shaft thereon carrying a sprocket wheel over which passes a sprocket chain or belt 72 extending over a wheel 73 mounted upon the shaft of the second cam, this shaft carrying a sprocket wheel or belt from which a chain 74 passes to the third speed selective gearing box designated 62b from which by means which will be obvious from the drawings, the power is transmitted to shaft of the third cam of the series. Thus each one of these three cams 61 may be driven at a different speed or at the same speed, if desired. The respective speeds of these cams, of course, determine the length of time during which the corresponding gates remain open. This period of time may be regulated also by means of the adjustable plate 60.

The same effect would be secured by using different formations of cam for the cams 61 but this would involve in case any change of time was required the stoppage of the machine and the replacement of the cams in use by other cams.

Thus, it will be seen that the mechanism which I have provided secures the same result without the necessity of stopping the machine by simply changing the speed of any particular cam or all of the cams by means of the selective speed transmission devices contained within the casings 62, 62a and 62b. The arms 55 are held upward and the arms 58 with their plates 60 are held against the cams 61 each by a spring 75, there being a separate spring for each arm 55 and corresponding arms 58, these springs being compression springs and bearing, at their lower ends, against the angle irons 76 attached to the wall of the shoe. Extending through each of these coiled compression springs 75 is a bolt 77 pivotally connected at its lower end to the corresponding arm 55 and at its upper end carrying a nut 78 bearing against a washer 79 in turn bearing against the coiled compression spring. Thus the tension of these springs may be adjusted and these springs act at all times to raise the arms 58 against the cams 61 and to hold the gates closed.

Extending over the top of each gate is a downwardly extending chute, these chutes being designated 80. The chutes at their upper ends are bent over the top of each gate and are supported thereon while the lower end of each chute 80 bears against an upturned lip 81

formed at the entrance end of the next succeeding deck, the lower end of each chute being held in place by means of the hold-down angle irons 82. Beyond the final deck 36, there is a final discharge chute 83 for the coal.

It will be seen by reason of the flexible couplings 29 that the shoe may be oscillated by means of the eccentric 22, these flexible couplings permitting this oscillation without any disconnection from the blowers or fan casings.

Preferably, the blast from each of these fans or to each of the compartments will be regulated, as for instance, by the dampers 84, 85 and 86, these dampers being independently rotatable into a more or less dampening position by means of the exterior handles 87 operating over a sector 88 arranged in conjunction with the handle to hold the handle at any adjusted position.

While I have referred heretofore to a depressed pocket 37 being formed at the discharge end of each deck, I wish it particularly understood that the form of this pocket may be varied in many ways and in Figures 8 to 11, I show four different ways in which this pocket may be formed. In Figure 8, the pocket 37 is formed by a downward inclination of the extremity of the curved deck. In Figure 9, the pocket 37a is formed by depressing the discharge end of the deck and then extending it horizontally. In Figure 10, the pocket 37b is formed as a downward depression of the deck, the outer wall of the pocket then rising upward toward the gate. In Figure 11, the pocket is not definitely distinguished from the deck but constitutes a practically straight continuation of the deck. This last named pocket or reservoir is suitable for an even flow of refuse of small amount. That form of the pocket shown in Figure 8 is suitable for a continuous large amount of rejection and its formation is extremely helpful in working the coal out of the slate because of the heavier down-grade push and the consequent squeezing effect. The pocket shown in Figure 9 is particularly suitable where the refuse comes down the deck in surges, sometimes more and sometimes less and of a heavy specific gravity while the pocket 37b shown in Figure 10 is suitable where only a small amount of rejection is maintained and where the coal is in fine particles having a maximum diameter of approximately one-eighth of an inch.

While I do not wish to be limited to this, I have illustrated the eccentric shaft 21 as being driven by a belt or sprocket chain 89 from the motor shaft 90 of a motor 91, the shaft of which extends into the first power transmission mechanism contained within the casing 62. It is again reiterated that I do not wish to be limited to the number of fans used. I have illustrated two fan casings, the first of which is connected to the first compartment A while the second fan compartment is connected and discharges into the compartments B and C but a fan may be used for each compartment desired or all three compartments may be connected to one fan. Neither do I wish to be limited to a structure having three compartments A, B and C with three decks, 34, 35, and 36 as it will be obvious that this cleaning machine may have a greater number of compartments arranged in series, if desired.

It is also pointed out that the refuse of the final deck in case of a multiple unit may be re-

turned to the original raw coal deck, that is, to the first deck of the series or to any other one of the series for retreatment. This refuse of the final deck is not as free from coal as the 5 refuse from the other decks which yield pure refuse because it represents the overflow surges of the other decks and at times there may be no refuse left from them and the final gate will discharge coal. By always carrying the coal 10 from the last gate of the deck back for treatment, a perfect refuse can be maintained and also a clean coal can be secured.

Where the coal is comparatively free from dust, a single fan may be used to operate a 15 multiple machine. This is also true where the quantity to be rejected is small.

It is also to be understood that I may use variable speed motors for the fans to control the amount of air which is forced up through each 20 deck or I may control the force of this air by means of dampers or dampers may be used in connection with a variable speed motor for the fan or fans or a constant speed motor may be used for all of the fans with selective speed mechanism.

It will be seen that I have provided a coal cleaner with a vibrating deck or decks incorporating all desirable slopes. Thus I secure the advantage of a steep slope which quickly thins 30 the tonnage at the feed and the advantage of a flatter slope which affords a more complete cleaning. These two slopes and the intermediate slopes are incorporated in a unit which gives results unequaled in separation. This slope, which 35 is in the form of a curved surface with the steepest portion at the feed end and its flattest portion at the discharge end, secures a uniform flotation without obstruction to the flow of the air such as adjustable or stationary valves, screens 40 or sandwiched granules of material between two screens. The maintaining of a freely flowing and comparatively unhindered velocity of air before it strikes the coal bed makes the nature of the bed practically the sole controlling means where- 45 by the desired pressure is held back to maintain a continued flotation. I thus secure a more thoroughly self-regulating flotation which automatically adapts itself to changes of the bed such as moisture content, percentages of fines, amount of 50 rejection and fracture variations of the particles. The bars 39 run transversely and parallel with the previous decking, check the flow of the coal, regulating its depth and impart vibration to it. These bars are adjustable upon the supporting 55 bar 41 as shown in Figure 5 so that the spacing from the decking may be varied.

These bars retard the coal, thereby giving the slate time in which to sink without sweeping it off with the downward sweep of the tonnage. 60 The bars do not retard the travel of the settled refuse which is traveling down beneath the bars but the bars make it possible to maintain a bed of predetermined depth. This is of advantage in that the thinnest possible bed which will hold 65 back enough pressure and velocity to place the coal in a state of flotation secures the cleanest results. This is obvious because a piece of slate will much more readily drop through a thin bed than a thicker one.

70 It will be seen that I have provided a cleaner which discharges its refuse through a mechanically operated gate at the discharge end of the cleaning surface. This gate in conjunction with the refuse reservoir or pocket formed immediately in advance of it, is so operated at stated in-

tervals, that only a portion of accumulation of refuse is dumped at each operation. The gate is adjustable as to the proportionate period of time that it is open relative to the time that it is closed. This is done by adjusting the sliding plate 60 5 against which the cam 61 operates. The time interval between dumpings is made possible by using a conventional speed change mechanism for operating the gates. I thus provide a controllable method of reject removal which is entirely positive and reliable, capable of producing a clean refuse without regard to clean or dirty surges of raw material. Obviously the raw material will vary largely with relation to the raw feed ash encountered because this raw feed ash 15 will come from different mines or sections.

It is particularly important that in my construction I give a motion of diminishing magnitude to the several tables or decks. This acts in conjunction with the slope of decreasing grade so 20 as to secure a particularly good cleaning result grading from a live and active application of power to a very gentle treatment and it is obvious that what is true of the series of decks is also true of any one deck, that its feed end is given a 25 larger amplitude of vibration than its discharge end. By giving a motion of diminishing magnitude and acting in conjunction with a slope of diminishing slant, all kinds of refuse of various sizes must sink at their ideal condition for settlement.

My cleaner is so constructed as to enable a multiple number of units to be made into one unit, thus affording a recleaning effect with comparatively small floor space and operation cost, and a successful recleaning of coal after its first treatment with air is made easy because this recleaned coal is no longer impregnated with fine dust which acts to seal the bed. In my machine, the first treatment dedusts the coal on a comparatively 40 small surface and requires comparatively little air. This is an economical advantage because the collection of this dust is a vital factor in overhead costs. A different condition exists after the dust has been blown off the coal and where only 45 single decks are used and the coal is being treated by only one fan. Under these circumstances, only a compromise treatment is possible, whereas as with my construction, the pressure volume and velocity of the air used in connection with one 50 deck may be varied from the pressure velocity and volume of air as used for the other deck. By the provision of a plurality of decks, coal of comparatively high moisture content may be treated successfully because the initial treatment 55 removes the objectional damp dust while the successive treatment removes the drier refuse from the remainder of the drier coal. The decking in my machine is easily accessible and replaceable and a much more substantial material can be 60 used than with other cleaners. This is due to the fact that the slate slides down grade instead of jiggling upward against gravity as is common practice with many present day cleaning systems. Furthermore the fact that the first deck 65 of the series removes the greatest amount of refuse material relieves the other decks of a proportionate amount of wear.

Another advantage in my construction resides 70 in the fact that it imparts little shock to a triple structure. Actual practice has shown that a vibrating mechanism constructed as in my machine produces a barely perceptible reaction.

Furthermore, I have provided a cleaner capa- 75

ble of cleaning coal with more foreign material therein and consequently more ash than is possible with any other cleaner to my knowledge. The operation of pneumatic cleaners has been a problem because a great amount of slate when settled would dampen the effective air velocity and hinder cleaning while if a sufficiently fast conveying system capable of removing this rapid accumulation were used, the effective separation would be destroyed. With my cleaner, the process may be repeated a sufficient number of times until the product is successfully cleaned. In other words, I may use any number of decks which may be desired.

I have demonstrated by test of this cleaner that machine cuttings of about twenty per cent ash will become a commercial product. These cuttings are ordinarily thrown away and many mines employing many men and which would otherwise be a valuable asset to industry cannot profitably operate because of their inability to cope with this problem.

While in many instances I have not found it necessary, yet in some circumstances, it is best to check the action of the spring 15 upon the corresponding gate by means of a dash pot or pneumatic or hydraulic check of any usual or suitable construction. I have illustrated this check generally in Figure 2 and designated it 55a.

It is to be understood that I do not wish to be limited to any particular curvature for the deck sections 34, 35 and 36 except as this may be stated in the accompanying claims. In actual practice, I have used a deck curvature struck on a radius of 100 inches for a twenty-four inch deck. The curvature of the deck is regular but the center of curvature is so placed toward the discharge end that its tangent at the high end makes an eight degree angle to the horizontal and the tangent makes a four degree angle to the horizontal at the low end. It will be understood, however, that the lengths of the radius will be changed depending upon the length of the deck.

The plate 60 attached to each of the arms 58 which operate the gates can be adjusted to change the length of time of the wiping engagement with the corresponding cam 61 without altering the shape of the cam. When the plate is shifted rearward on the arm 58 to its shortest position, the point of the cam will trip the gate when it stands vertically downward. By sliding the plate 60 out as far as it will go, the point of the cam will trip at an angle far beyond the vertical, the closing action of the gate beginning at the time of tripping.

By this adjustment, I can secure any desired ratio of open and closed position for the gate. I can have a fifty per cent open and a fifty per cent time closed period or a twenty-five per cent open and a seventy-five per cent closed period. I find that with a twenty-five per cent open and a seventy-five per cent closed ratio, the refuse concentration is thereby favored and the result is remarkably improved. Obviously the cam 61 could be changed in shape to give this result, but the same result is secured in a much simpler way and in an easily adjustable manner by sliding the plate 60 forward or rearward upon the arm 58. It will be seen that the selective speed devices control the number of gate actions per minute while the adjustment of the plate 60 controls the relative length of time that the gate is opened and dumping as against the length of time the gate is closed and concentrating refuse. Without this result secured by the adjustable plate 60

or by the cam 61, it would not be possible to discharge pure refuse from so small a reservoir as I must use. The gate is adjustable vertically, that is, the lower edge of each gate 49 is provided with the adjustable member 51 and is necessary 5 in order to adjust the depth of bed in conjunction with the transversely extending bars. The deck may be made of perforated metal or of reticulated or woven wire, and any number of perforations per square inch or the mesh will depend upon the work to be done. 10

It is to be noted that the eccentric 22 is both vertical and longitudinal oscillation to the deck and the tossing motion thus secured I find is very necessary.

While I have illustrated certain details of construction and certain specific arrangements of parts, I do not wish to be limited to these details as it is obvious that many changes might be made in these details without departing from the spirit 20 of the invention as defined in the appended claims. I do not wish to be limited to the linkage used for the gate mechanism as it is obvious that the gate may be opened or closed by other mechanism than that shown, or, in other words, 25 it is the provision of discharge gates for the refuse which open intermittently that is one of the points of this invention and not the specific means whereby these gates are intermittently opened.

The slant of the deck or sections of the deck 30 is an extremely important matter because the degree of this slant determines the ease of flow and the ease of flow in turn determines the force with which the air holds the particles in suspension. If the surface of the deck is horizontal, the 35 air will exert a direct force and as the slant increases the lifting force of the air correspondingly decreases because the coal and culm slip away easier. Since the slope varies the lifting force, it affects the separation. Since the exact degree 40 of lift required to float the coal without floating the slate is always a matter of experiment and can only be accomplished with the correct slope for a definite quality of coal, it follows that any arbitrary slope cannot be correctly predeter- 45 mined because the coal constantly varies and an arbitrary fixed slant at one particular angle would not vary with all the variance present under operating conditions. The refuse to be removed is not all one kind and this refuse constantly varies. There will be sandstone, slate, 50 clay and matter of entirely different characteristics and sizes, all of which have different tendencies with respect to flotation. Sometimes, the refuse is flat and floats easily on top of the mass. 55 This, of course, is entirely undesirable. Sometimes the coal is relatively heavy and needs more air to keep it buoyed up but it is not likely, once it is up, to sink down through the slate provided the treatment surface helps it to remain up. My 60 treatment surface provides a deck or series of decks which varies gradually in its slant or pitch. Preferably, this variation is from 40° to 12°, which presents a surface at some point along its length of correct slant. In my deck, the slant 65 is continually but gradually varied and thus the instant the coal mixture passes over the correct point, that is, a point having the correct slant, it is cleaned because the lifting at this point is just correct to raise the coal and not 70 raise the slate. The deck, therefore, must gradually and smoothly vary its amount of slant.

The tendency of a highly inclined slope not constantly varying in its slant is to let the air pass through or pipe through with excessive 75

blowing at the entry end. This breaks up flotation. This is because the mixture changes as it progresses and the slope must also change to keep a lifting effect in proportion to the mixture.

Generally speaking, my invention includes decks having all degrees of slope such as are necessary for the forward travel of the material and its effective cleaning, each slope having its work to do. This secures a smooth flotation and cleaning effect without the necessity of manipulating any valves or providing power consuming obstructions.

As before stated, the intermittently operated gates 49 are extremely important features in my invention. It is known to provide gates which are adjusted to the size coal to be passed, as for instance, coal ranging from one-half inch to a very small grain. With a gate which is open constantly to permit the passage of half inch coal, it is impossible to keep the refuse pure because the refuse drains away from beneath the coal itself too fast. An amount of refuse, therefore, must be held back so as to keep the coal from draining away with the refuse. By my invention, the gate is closed a predetermined period which holds the refuse back, then the gate is opened for a predetermined period, and the refuse is carried off but without draining the coal because the gate closes before the coal on top of the refuse can be drained and it will be seen that with my construction, the length of time that the gates are held closed and the length of time they are held open may be varied and it will likewise be seen that each gate may be held open or closed a length of time differing from the timing of any other gate.

I claim:-

1. A coal cleaner including a pervious deck disposed at a gradually decreasing slant from its entrance to its discharge end, baffle rods extending at intervals transversely above the deck, in spaced relation thereto, the series of baffle rods following the contour of the deck, means for discharging air upwardly through the deck, and means for oscillating the deck, the pivotal center of oscillation being relatively adjacent the discharge end of the deck.

2. A coal cleaner including a body having lateral walls, a pervious deck disposed between said walls, the deck being disposed at a gradually decreasing slant from its entrance to its discharge end, a series of baffle rods extending transversely across the deck but in spaced relation thereto, and following the contour of the deck, and means for individually adjusting said baffle rods including members adjustably engaging the walls of the body.

3. A coal cleaner including a body having lateral walls, a series of pervious decks disposed between said walls and discharging one upon the other, each of said decks being disposed at a gradually decreasing slant from its entrance to its discharge end, means for discharging air upwardly through said decks, and means for giving to all of said decks, oscillations of an amplitude gradually decreasing from the entrance end of the first deck to the exit end of the last deck.

4. In a coal cleaner, a series of rigidly connected and successive decks discharging one upon the other, the decks receiving raw feed at one end and discharging cleaned coal at the other end, the decks being pervious and each deck be-

ing disposed at a gradually decreasing slant from its entrance to its discharge end, means for giving to the series of decks, vertical and longitudinal oscillations of an amplitude decreasing from the entrance end of the first deck of the series to the discharge end of the last deck of the series, means for forcing air upward through the several decks, and means for discharging refuse from the discharge end of each deck of the series.

5. A coal cleaner including a series of rigidly connected and successive decks receiving raw feed at one end and discharging cleaned coal at the other, each deck being pervious and being disposed at a gradually decreasing slant from its entrance end to its discharge end, a refuse chute at the discharge end of each deck, a valve extending above the deck and controlling the discharge into said chute, power operated means for intermittently opening each valve, a coal chute extending over the top of each valve and receiving coal from one deck and discharging it on to the next successive deck, and means for discharging air upward through the several decks.

6. A coal cleaner including a plurality of decks arranged in a rigidly connected series, receiving raw feed at one end and discharging cleaned coal at the other, each deck being pervious and being disposed at a gradually decreasing slant from its entrance to its discharge end, refuse chutes disposed at the discharge end of each deck, a gate controlling the passage of refuse to each chute, each gate extending above the discharge end of the corresponding deck and being mounted for swinging movement away from the deck, means for intermittently opening said gates, said means permitting the independent timing of the gates, a coal chute extending over the top of each gate and discharging downward on to the next successive deck of the series, and independently controllable means for discharging air upward through the several decks.

7. A coal cleaner including a body having side walls and a series of successive decks rigidly engaged with the side walls, said decks being pervious and each deck being disposed on a gradually decreasing slant from its entrance to its discharge end, means for discharging refuse from the discharge end of each deck, means for carrying coal from the discharge end of each deck over on to the entrance end of the next successive deck, means for discharging air upwardly through the several decks and independently controlling the velocity or pressure of the air for each deck, a supporting frame, laterally disposed elements rigidly connected to the side walls of the body and being pivotally supported upon said supporting frame at a point below the discharge end of the body, an eccentric supported upon the supporting frame, eccentric straps coacting with the eccentric and operatively connected to said elements, the eccentric straps being connected to the ends of the elements adjacent the entrance end of the body, and means for driving said eccentric.

8. A coal cleaner of the character described including a body having side walls, a series of decks disposed between and rigidly connected to the side walls, the decks being pervious and the discharge end of one deck being spaced from the entrance end of the next succeeding deck, each deck being disposed on a gradually decreasing slant from its entrance to its discharge end, channel members, main refuse chutes rigidly connected to the side walls of the body, a support-

ing frame, a pivotal connection between the supporting frame and said channel members adjacent the discharge end of the body, power operated means carried by the supporting frame for oscillating the opposite ends of said channel members and the body, refuse chutes into which the discharge end of each deck discharges, the said chutes discharging into said main refuse channel members swinging the gates disposed at the discharge ends of each of the decks and controlling the passage of refuse into the discharge chutes, coal chutes extending over the top of the gates and extending downward on to the entrance end of the next successive deck, power operated means for intermittently opening and closing the several gates, the power operated means for each gate being independently controllable, means for discharging air upward through said several decks, and independently controlling the pressure and velocity for each deck, and means for maintaining a bed of refuse upon each deck and a superincumbent bed of coal upon each deck and comprising a series of transverse baffle bars extending transversely across above the deck and in predetermined spaced relation thereto and to each other.

9. A coal cleaner including a body having side walls, a series of pervious decks disposed between the side walls and receiving raw feed at one end and discharging cleaned coal at the other, the discharge end of one deck being spaced from the receiving end of the next successive deck, each deck being disposed on a gradually decreasing slant from its entrance to its discharge end, each deck adjacent its discharge end being formed to provide a refuse detaining pocket, a swinging gate at the discharge end of each deck and extending above the deck and controlling the discharge of refuse therefrom, means for intermittently opening said gates, a chute extending over the top of each gate and downward to receiving end of the next succeeding deck, baffle bars extending transversely across above each deck and disposed in predetermined spaced relation to the deck and following the contour thereof, those bars above the refuse pocket being disposed divergently with relation thereto whereby to maintain a bed of coal above the bars and a bed of refuse below the bars, means for controllably discharging air upward through each deck, the air controlling means for one deck being independently adjustable with relation to the air controlling means of any other deck, and means for oscillating said body and the decks, said means giving to the decks and body a gradually decreasing oscillation from the entrance end of the body to the discharge end thereof.

10. A coal cleaner including a pervious deck having a gradually varying slant from its entrance to its discharge end, baffle rods extending at intervals transversely above the deck in spaced relation thereto, the baffle rods following the contour of the deck, means for discharging air upwardly through the deck, and means for giving the deck an oscillatory movement of gradually decreasing amplitude toward its discharge end.

11. In a coal cleaner, a series of downwardly inclined pervious deck sections, means for discharging air upwardly through the deck sections to float the light coal and permit the heavy refuse to sink on to the deck sections, transversely extending spaced bars disposed immediately above each deck section and approximately conform-

ing in inclination thereto and acting to assist in supporting the coal above the refuse and permit the refuse to sink between the bars, means for discharging air upward through the deck sections to float the light coal and permit the heavy refuse to sink, a refuse gate at the discharge end of each deck section, means extending over the gate for guiding the coal over said gate and on to the entrance end of the next succeeding section, means for intermittently lifting and closing said gates, and means coacting with each gate whereby the time that it remains lifted and remains closed may be independently varied.

12. A coal cleaner including a pervious deck disposed at a constantly varying slant from its entrance to its discharge end, an air trunk extending directly downward from the deck and having the same cross-sectional area as the deck, means for discharging air upwardly through the trunk and the deck, a series of rods extending at intervals transversely above the deck and in spaced relation thereto, the series of rods approximately following the contour of the deck and means for giving the deck an oscillatory movement in a vertical plane.

13. A coal cleaner of the character described, comprising a pervious deck disposed at an inclination downwardly from its entrance to its discharge end, walls disposed at opposite sides of the deck and projecting above the same, a pair of angle bars disposed against the inner side of each wall and extending longitudinally of the deck and each having an angular portion extending inwardly from the wall, a plurality of rod members disposed in spaced parallel relation above and in spaced relation with the deck and transversely of the same and attached at their ends to the adjacent inwardly extending angle bar portions, means connecting said angle bars with the walls facilitating the vertical adjustment of the bars thereon relative to the deck, an air trunk extending downwardly from the under side of the deck, and means for discharging air upwardly through the trunk against a bed of coal resting on said bars over the deck.

14. In a coal cleaner of the character described, a pervious deck disposed at a downward inclination from its entrance to its discharge end, an air trunk extending downwardly from the under side of the deck, means for discharging air upwardly through the trunk against a bed of coal disposed over the deck, means for oscillating the deck, a refuse chute disposed across the discharge end of the deck, a shaft extending transversely of the deck in spaced relation with and at the discharge end of the same, a refuse gate comprising a plate having an edge portion attached to said shaft and extending downwardly toward the adjacent plate, the shaft and plate being oscillatable for the discharge of refuse from the deck into the chute, means for carrying coal over the gate and refuse chute, comprising a plate extending transversely of the deck and across the chute at a downward inclination from said shaft, said last plate being attached along one edge to the shaft, supporting means for said shaft at each end of the same and adapted to facilitate the raising or lowering of the same together with the refuse gate and the last mentioned plate attached thereto, and means for intermittently oscillating the gate.
